(57) CLAIM

The ornamental design for a solar panel, as shown and described.

DESCRIPTION

FIG. 1 is a front, right-side, and bottom perspective view of a solar panel showing our new design according to a first embodiment.

FIG. 2 is a rear, right-side, and bottom perspective view of the solar panel of FIG. 1.

FIG. 3 is a front view of the solar panel of FIG. 1.

FIG. 4 is a rear view of the solar panel of FIG. 1.

FIG. 5 is a right-side view of the solar panel of FIG. 1.

FIG. 6 is a left-side view of the solar panel of FIG. 1.

FIG. 7 is a top view of the solar panel of FIG. 1.

FIG. 8 is a bottom view of the solar panel of FIG. 1.

FIG. 9 is a front, right-side, and bottom perspective view of a solar panel showing our new design according to a second embodiment.

FIG. 10 is a rear, right-side, and bottom perspective view of the solar panel of FIG. 9.

FIG. 11 is a front view of the solar panel of FIG. 9.

FIG. 12 is a rear view of the solar panel of FIG. 9.

FIG. 13 is a right-side view of the solar panel of FIG. 9.

FIG. 14 is a left-side view of the solar panel of FIG. 9.

FIG. 15 is a top view of the solar panel of FIG. 9.

FIG. 16 is a bottom view of the solar panel of FIG. 9.

FIG. 17 is a front, right-side, and bottom perspective view of a solar panel showing our new design according to a third embodiment.

FIG. 18 is a rear, right-side, and bottom perspective view of the solar panel of FIG. 17.

FIG. 19 is a front view of the solar panel of FIG. 17.

FIG. 20 is a rear view of the solar panel of FIG. 17.

FIG. 21 is a right-side view of the solar panel of FIG. 17.

FIG. 22 is a left-side view of the solar panel of FIG. 17.

FIG. 23 is a top view of the solar panel of FIG. 17.

FIG. 24 is a bottom view of the solar panel of FIG. 17.

FIG. 25 is a front, right-side, and bottom perspective view of a solar panel showing our new design according to a fourth embodiment.

FIG. 26 is a rear, right-side, and bottom perspective view of the solar panel of FIG. 25.

FIG. 27 is a front view of the solar panel of FIG. 25.

FIG. 28 is a rear view of the solar panel of FIG. 25.

FIG. 29 is a right-side view of the solar panel of FIG. 25.

FIG. 30 is a left-side view of the solar panel of FIG. 25.

FIG. 31 is a top view of the solar panel of FIG. 25.

FIG. 32 is a bottom view of the solar panel of FIG. 25.

FIG. 33 is a front, right-side, and bottom perspective view of a solar panel showing our new design according to a fifth embodiment.

FIG. 34 is a rear, right-side, and bottom perspective view of the solar panel of FIG. 33.

FIG. 35 is a front view of the solar panel of FIG. 33.

FIG. 36 is a rear view of the solar panel of FIG. 33.

FIG. 37 is a right-side view of the solar panel of FIG. 33.

FIG. 38 is a left-side view of the solar panel of FIG. 33.

FIG. 39 is a top view of the solar panel of FIG. 33.

FIG. 40 is a bottom view of the solar panel of FIG. 33.

FIG. 41 is a front, right-side, and bottom perspective view of a solar panel showing our new design according to a sixth embodiment.

FIG. 42 is a rear, right-side, and bottom perspective view of the solar panel of FIG. 42.

FIG. 43 is a front view of the solar panel of FIG. 42.

FIG. 44 is a rear view of the solar panel of FIG. 42.

FIG. 45 is a right-side view of the solar panel of FIG. 42.

FIG. 46 is a left-side view of the solar panel of FIG. 42.

FIG. 47 is a top view of the solar panel of FIG. 42.

FIG. 48 is a bottom view of the solar panel of FIG. 42.

FIG. 49 is a front, right-side, and bottom perspective view of a solar panel showing our new design according to a seventh embodiment.

FIG. 50 is a rear, right-side, and bottom perspective view of the solar panel of FIG. 49.

FIG. 51 is a front view of the solar panel of FIG. 49.

FIG. 52 is a rear view of the solar panel of FIG. 49.

FIG. 53 is a right-side view of the solar panel of FIG. 49.

FIG. 54 is a left-side view of the solar panel of FIG. 49.

FIG. 55 is a top view of the solar panel of FIG. 49.

FIG. 56 is a bottom view of the solar panel of FIG. 49.

FIG. 57 is a front, right-side, and bottom perspective view of a solar panel showing our new design according to an eighth embodiment.

FIG. 58 is a rear, right-side, and bottom perspective view of the solar panel of FIG. 57.

FIG. 59 is a front view of the solar panel of FIG. 57.

FIG. 60 is a rear view of the solar panel of FIG. 57.

FIG. 61 is a right-side view of the solar panel of FIG. 57.

FIG. 62 is a left-side view of the solar panel of FIG. 57.

FIG. 63 is a top view of the solar panel of FIG. 57.

FIG. 64 is a bottom view of the solar panel of FIG. 57.

FIG. 65 is a front, right-side, and bottom perspective view of a solar panel showing our new design according to a ninth embodiment.

FIG. 66 is a rear, right-side, and bottom perspective view of the solar panel of FIG. 65.

FIG. 67 is a front view of the solar panel of FIG. 65.

FIG. 68 is a rear view of the solar panel of FIG. 65.

FIG. 69 is a right-side view of the solar panel of FIG. 65.

FIG. 70 is a left-side view of the solar panel of FIG. 65.

FIG. 71 is a top view of the solar panel of FIG. 65.

FIG. 72 is a bottom view of the solar panel of FIG. 65.

FIG. 73 is a front, right-side, and bottom perspective view of a solar panel showing our new design according to a tenth embodiment.

FIG. 74 is a rear, right-side, and bottom perspective view of the solar panel of FIG. 73.

FIG. 75 is a front view of the solar panel of FIG. 73.

FIG. 76 is a rear view of the solar panel of FIG. 73.

FIG. 77 is a right-side view of the solar panel of FIG. 73.

FIG. 78 is a left-side view of the solar panel of FIG. 73.

FIG. 79 is a top view of the solar panel of FIG. 73.

FIG. 80 is a bottom view of the solar panel of FIG. 73.

FIG. 81 is a front, right-side, and bottom perspective view of a solar panel showing our new design according to an eleventh embodiment.

FIG. 82 is a rear, right-side, and bottom perspective view of the solar panel of FIG. 81.

FIG. 83 is a front view of the solar panel of FIG. 81.

FIG. 84 is a rear view of the solar panel of FIG. 81.

FIG. 85 is a right-side view of the solar panel of FIG. 81.

FIG. 86 is a left-side view of the solar panel of FIG. 81.

FIG. 87 is a top view of the solar panel of FIG. 81.

FIG. 88 is a bottom view of the solar panel of FIG. 81.

FIG. 89 is a front, right-side, and bottom perspective view of a solar panel showing our new design according to a twelfth embodiment.

FIG. 90 is a rear, right-side, and bottom perspective view of the solar panel of FIG. 89.

FIG. 91 is a front view of the solar panel of FIG. 89.

FIG. 92 is a rear view of the solar panel of FIG. 89.

FIG. 93 is a right-side view of the solar panel of FIG. 89.

FIG. 94 is a left-side view of the solar panel of FIG. 89.

FIG. 95 is a top view of the solar panel of FIG. 89.

FIG. 96 is a bottom view of the solar panel of FIG. 89.

FIG. 97 is a front, right-side, and bottom perspective view of a solar panel showing our new design according to a thirteenth embodiment.

FIG. 98 is a rear, right-side, and bottom perspective view of the solar panel of FIG. 97.

FIG. 99 is a front view of the solar panel of FIG. 97.

FIG. 100 is a rear view of the solar panel of FIG. 97.

FIG. 101 is a right-side view of the solar panel of FIG. 97.

FIG. 102 is a left-side view of the solar panel of FIG. 97.

FIG. 103 is a top view of the solar panel of FIG. 97.

FIG. 104 is a bottom view of the solar panel of FIG. 97.

FIG. 105 is a front, right-side, and bottom perspective view of a solar panel showing our new design according to a fourteenth embodiment.

FIG. 106 is a rear, right-side, and bottom perspective view of the solar panel of FIG. 105.

FIG. 107 is a front view of the solar panel of FIG. 105.

FIG. 108 is a rear view of the solar panel of FIG. 105.

FIG. 109 is a right-side view of the solar panel of FIG. 105.

FIG. 110 is a left-side view of the solar panel of FIG. 105.

FIG. 111 is a top view of the solar panel of FIG. 105.

FIG. 112 is a bottom view of the solar panel of FIG. 105.

FIG. 113 is a front, right-side, and bottom perspective view of a solar panel showing our new design according to a fifteenth embodiment.

FIG. 114 is a rear, right-side, and bottom perspective view of the solar panel of FIG. 113.

FIG. 115 is a front view of the solar panel of FIG. 113.

FIG. 116 is a rear view of the solar panel of FIG. 113.

FIG. 117 is a right-side view of the solar panel of FIG. 113.

FIG. 118 is a left-side view of the solar panel of FIG. 113.

FIG. 119 is a top view of the solar panel of FIG. 113; and,

FIG. 120 is a bottom view of the solar panel of FIG. 113.

The portions of the solar panel rendered in short broken lines form no part of the claimed design.
